UNITED STATES PATENT OFFICE.

WILLIAM M. AMMERMAN, OF NEW HAVEN, CONNECTICUT, ASSIGNOR, BY MESNE
ASSIGNMENTS, TO ANNIE ELIZABETH AVERY, ADMINISTRATRIX.

CLUTCH.

No. 900,052.

Specification of Letters Patent. Patented Sept. 29, 1908.

Application filed March 3, 1906. Serial No. 303,950.

To all whom it may concern:

Be it known that I, WILLIAM M. AMMERMAN, a citizen of the United States, and resident of New Haven, in the county of New Haven and State of Connecticut, have invented certain new and useful Improvements in Clutches, of which the following is a specification.

This invention relates to improvements in 10 clutches and has more particular reference to improvements in that class of clutches adapted for effecting connection and disconnection between the hand-wheel of a sewing machine, which is made fast to the sewing 15 machine driving shaft, and the driving belt-wheel or pulley which is mounted on the machine adjacent to said hand-wheel and which receives its motion from a suitable source of power through the medium of a belt.

20 The object of the invention is to provide an improved clutch, adapted for general use but more particularly for use in connection with sewing machines as above referred to, which will be simple in construction, effective in 25 operation, and capable of ready and convenient adjustment. These objects are attained in a preferred embodiment of my invention by means of a clutch element made in the form of a rocker-cam supported in the 30 hand-wheel hub and being movable to and from an operative position of clutching engagement with the belt-wheel hub, and a clutch-operating element made in the form of a cap rotatably mounted on the outer end of 35 the hand-wheel hub and having operative connection with the said clutch element.

Referring now to the accompanying drawing illustrating my invention and which forms a part of this specification—Figure 1 40 is a front elevation of the rear end of a sewing machine broken away and having my improved clutch applied thereto. Fig. 2 is an enlarged detail end view of the central clutch embodying portions of the sewing machine 45 hand and belt wheels, looking from the right in Fig. 1 and showing the clutch-operating element. Fig. 3 is a central longitudinal section through the said clutch embodying portions of the hand and belt wheels shown 50 in Fig. 2. Figs. 4 and 5 are cross-sections on the line x—x of Fig. 3, showing the clutch element in clutching and unclutching positions respectively. Fig. 6 is a detail view of the clutch operating or adjusting element look-

ing toward the inner end thereof, and Fig. 7 55 is a detail view of the clutch element.

In said drawings, 1 indicates a portion of a sewing machine arm in the upper part of which is journaled the sewing machine driving shaft 2 which is arranged with one end 60 thereof projecting beyond the end of the arm 1 and having mounted thereon the hand-wheel 3 and the belt-wheel 4, the said hand-wheel being made fast to the shaft and the belt-wheel being loose thereon and adapted 65 to be clutched to and unclutched from said hand-wheel whereby it may be caused to either impart motion to the machine or to run independent thereof when the bobbin-winding attachment 5 is to be operated. 70 These several parts 1 to 5, as described, are of usual arrangement and operation, excepting as hereinafter specified.

The hand-wheel 3 is provided with the usual centrally located hub to receive the 75 driving shaft, which hub in the present case projects at each side of the wheel, with the end 6 at the inner side of the wheel being somewhat more extended than the opposite end 7 at the outer side of the wheel and having 80 rotatably mounted thereon the belt-wheel 4. Within a partially cylindrical shaped seat 8 formed in the hub of the hand-wheel parallel with its axis and opening through the outer surface of the hub opposite the inner wall 9 of the belt-wheel hub 10 is loosely seated the clutch element 11. This clutch element as shown is made in the form of a rocker-cam so designed as to lie wholly 85 within the plane of the outer surface of the hub 6 and away from engagement with the wall 9 of the belt-wheel hub when in unclutching position, as shown in Figs. 3 and 5, or to partially project above the plane of the surface of the hub 6 and engage with the 90 said wall 9 of the belt-wheel hub when in clutching position, as shown in Fig. 4. As a simple and effective means for operating the said rocker-cam to move it to and from its operative position of clutching engagement 100 with the belt-wheel, I have provided the same at its outer end with a crank-arm or extension 12 which has a pin-and-slot connection with an operating cap-piece 13 rotatably mounted on the outer end 7 of the 105 hand-wheel hub; the said pin-and-slot connection between the crank-arm and the cap-piece as herein shown comprising a pin 14

- on the crank-arm extending into an elongated slot 15 in the cap-piece. By turning the cap-piece 13 in the proper direction it will operate through the connecting crank-
5 arm 11 to move or rock the clutch cam either to or from its operative clutching position, in manner as clearly illustrated in Figs. 4 and 5.
- The clutch-operating cap-piece 13 may be
10 operatively retained in position on the hand-wheel hub 7 by any suitable means, the means employed for such purpose in the present case comprising an inwardly-turned lip 16 on the cap-piece engaging the hub 7
15 within an annular groove 17 therein, as clearly shown in Fig. 3; such connection serving to hold the cap-piece against endwise displacement on the hub while permitting its rotary movement thereon.
- 20 What I claim is:
1. The combination of a shaft, a wheel connected thereto to rotate therewith, said wheel having a hub formed with a longitudinal seat, an element rotatably mounted on said hub, a clutch comprising a rocker cam supported in said seat and extending within the hub of said rotatable element, said clutch being movable to and from an operative position of clutching engagement with said rotatable element, a cap rotatably mounted on the hub of said wheel and a loose connection between said cap and clutch element.
  2. The combination of a wheel having a hub, a second wheel rotatably mounted on one end of said hub, a clutch comprising a rocker-cam mounted in the hub of the first-mentioned wheel and being movable to and from an operative position of clutching engagement with the second-mentioned wheel, and a cap rotatably mounted on the end of the hub of the first-mentioned wheel oppo-
- site to that carrying said second wheel and having connection with the said cam for moving it to and from its said operative position.
3. A sewing machine hand-wheel having a hub projecting at each side thereof, said hub having a longitudinal seat, a belt-wheel or pulley rotatably mounted on the hub of said hand-wheel at one side thereof and covering said seat, a cap rotatably mounted on the hub of the hand-wheel at that side thereof opposite the said belt-wheel, and a clutch comprising a rocker-cam mounted in the seat in the hub of the hand-wheel and extending within the hub of the belt wheel and being movable to and from an operative position of clutching engagement with the belt-wheel and having connection with the said rotatable cap to be operated thereby.
4. The combination of a sewing machine hand-wheel having a hub projecting at each side thereof, a belt-wheel or pulley rotatably mounted on the hub of said hand-wheel at one side thereof, a cap rotatably mounted on the hub of said hand-wheel at that side thereof opposite the said belt-wheel, means for holding the cap against endwise displacement from the hand-wheel hub, and a clutch comprising a rocker-cam mounted in the hub of the hand-wheel and being movable to and from an operative position of clutching engagement with the belt-wheel and having connection with the said cap to be operated thereby.

Signed at New Haven in the county of New Haven and State of Connecticut this 21st day of February, A. D. 1906.

WILLIAM M. AMMERMAN.
